CLAIM

I claim the ornamental design for an air deodorizing apparatus, as shown and described.

DESCRIPTION

FIG. 1 is a front perspective view of an air deodorizing apparatus comprising the present invention.

FIG. 2 is a front elevational view of the air deodorizing apparatus shown in FIG. 1.

FIG. 3 is a rear elevational view of the air deodorizing apparatus shown in FIG. 1 and FIG. 2.

FIG. 4 is a side elevational view of the air deodorizing apparatus shown in FIG. 1, FIG. 2, and FIG. 3.

FIG. 5 is another side elevational view of the air deodorizing apparatus shown in FIG. 1, FIG. 2, FIG. 3, and FIG. 4.

FIG. 6 is a top plan view of the air deodorizing apparatus shown in FIG. 1, FIG. 2, FIG. 3, FIG. 4 and FIG. 5; and, FIG. 7 is a bottom plan view of the air deodorizing apparatus shown in FIG. 1, FIG. 2, FIG. 3, FIG. 4 and FIG. 5.

The broken line showing of the electrical plug on the air deodorizing apparatus is for illustrative purposes only and forms no part of the claimed design.
